E. D. BLOOMFIELD,
SLEEPING HOOD,
APPLICATION FILED DEC. 14, 1916.

1,235,419.

Patented July 31, 1917.

UNITED STATES PATENT OFFICE.

EMMA D. BLOOMFIELD, OF HOUSTON, TEXAS.

SLEEPING-HOOD.

1,235,419.

Specification of Letters Patent. Patented July 31, 1917.

Application filed December 14, 1916. Serial No. 136,953.

To all whom it may concern:

Be it known that I, EMMA D. BLOOMFIELD, a citizen of the United States, residing at Houston, in the county of Harris 5 and State of Texas, have invented certain new and useful Improvements in Sleeping-Hoods, of which the following is a specification.

My invention relates to a hood adapted 10 to be worn upon the head when sleeping and carrying means for holding the mouth of the wearer closed, whereby breathing through the mouth is prevented.

An important object of the invention is to 15 provide a device of the above mentioned character, which is simple in construction, inexpensive to manufacture, and convenient and comfortable in use.

Other objects and advantages of the invention will be apparent during the course 20 of the following description.

In the accompanying drawings forming a part of this specification and in which like numerals are employed to designate like 25 parts throughout the same,

Figure 1 is a perspective view of a device embodying the invention, showing the same in use.

Fig. 2 is a similar view showing the same 30 removed,

Fig. 3 is a detailed section through a chin receiving portion of the device, and,

Fig. 4 is a bottom plan view of a switch receiving loop.

35 In the drawings, wherein for the purpose of illustration is shown a preferred embodiment of my invention, the numeral 5 designates the body portion of the hood, which may be formed of an open fabric, such as

40 gauze, net, or any other suitable material, adapted to be laundried. Secured to this body portion, by stitching or the like is a front section 5', which is formed of an open fabric, as shown. The front section 5' has 45 a tuck 6 formed therein and stitched at 7, and this tuck may be released by removing the stitching. By this means the size of the hood may be somewhat adjusted.

Secured to the top portion of the front 50 section 5' is a strip of relatively nonextensible fabric or tape 8, to the lower ends of which are attached a longitudinally elastic band 9, preferably formed of rubber, while it may be made of elastic webbing. The 55 connection between the end or ends of the elastic band 9 and the strip 8 is preferably

adjustable, so that the device may be worn upon heads of different sizes, but the specific form of adjustable connecting means is immaterial. Strips of tape 10 or the like 60 are attached to the strip 8 and the lower tape or strip 12, which is attached to the lower end of the hood and has its ends extending forwardly therebeyond for a substantial distance. 65

The numeral 9' designates a relatively non-elastic flexible chin engaging band, secured to the band 9, and forming therewith a chin receiving pocket.

Surrounding the band 9 is a loop 13, 70 adapted to receive the ends of the tape 12, as clearly illustrated in Fig. 1.

As clearly shown in Figs. 2 and 4, a tape 14 is attached to the rear portion of the tape 12, inwardly thereof, forming a loop 75 for receiving the plait of the wearer.

In use, the device is placed on the head, as clearly illustrated in Fig. 1, with the elastic strip 9 beneath and the band 9' in advance of the chin, as shown in Fig. 1. If 80 the wearer has a plait, it is passed through the plait receiving loop 14, thereby holding the device securely in place upon the wearer, when the ends of the tape 12 are passed through the loop 13 and then tied. 85 Some degree of success is obtained by omitting the plait receiving loop.

It is to be understood that the form of my invention herewith shown and described is to be taken as a preferred example of 90 the same, and that various changes in the shape, size, and arrangement of parts may be resorted to without departing from the spirit of the invention or the scope of the subjoined claims. 95

Having thus described my invention, I claim:

1. A device of the character described, comprising a body portion to receive the head of the wearer and formed of open 100 fabric, a relatively non-extensible strip secured to the upper portion of the body portion at its forward edge, a longitudinally elastic band connected with the nonextensible strip and adapted to be passed beneath 105 the chin, a loop carried by the elastic band, a tape secured to the lower end of the body portion and extending forwardly therebeyond and adapted to be passed about the neck and tied to the loop, and a plait receiving loop secured to the rear portion of 110 the tape,

2. A device of the character described, comprising a body portion to receive the head of the wearer and formed of open fabric, a relatively non-extensible strip secured to the upper portion of the body portion at its forward edge, a longitudinally elastic band connected with the non-extensible strip and adapted to be passed beneath the chin, a loop carried by the elastic band, a tape secured to the lower end of the body portion and extending forwardly therebeyond and adapted to be passed about the neck and tied to the loop, and a band secured to the elastic band and adapted to be arranged in contact with the chin and disposed forwardly thereof.

3. A device of the character described, comprising a body portion to receive the head of the wearer and formed of open fabric, a relatively non-extensible strip secured to the upper portion of the body portion at

its forward edge, a longitudinally elastic band connected with the non-extensible strip and adapted to be passed beneath the chin, a loop carried by the elastic band, a tape secured to the lower end of the body portion and extending forwardly therebeyond and adapted to be passed about the neck and tied to the loop, and a band secured to the elastic band and adapted to be arranged in contact with the chin and disposed forwardly thereof.

In testimony whereof I affix my signature in presence of two witnesses.

EMMA D. BLOOMFIELD.

Witnesses:

WALTER F. BROWN,
LOUIS LARSEN.
